UNITED STATES PATENT OFFICE.

FRIEDRICH CHRISTIANSEN, OF KIEL, GERMANY.

LIFE-BELT.

1,049,563.

Specification of Letters Patent.

Patented Jan. 7, 1913.

Application filed October 2, 1912. Serial No. 723,576.

To all whom it may concern:

Be it known that I, FRIEDRICH CHRISTIANSEN, a subject of the King of Prussia, and resident of No. 20 Eckernförder Allée, Kiel, 5 in the Empire of Germany, have invented a new and useful Improved Life-Belt, of which the following is a specification.

The present invention relates to an improved marine life-saving device in the 10 shape of a life-belt, the float of which carries an oil reservoir set in action when the device enters the water, so that the waves around the device are suppressed. The life belt thus floating on calmed water affords to 15 the person or persons using the same an efficient protection against the dangerous force of the waves. Apart from this advantage, the oil-issuing life-belts thrown out for life-saving purposes are easier located both 20 by the persons to be saved and by the crew attempting the rescue from the ship or boat.

Special objects of the invention are to render more efficient, serviceable and durable in operation devices of the kind referred to.

25 With these ends in view the invention consists in the novel combination, arrangement and adaptation of parts all as more fully hereinafter explained, shown in the accompanying drawings and then specifically set 30 out in the appended claims.

In the drawing Figure 1 shows the life-boat, provided with an oil reservoir according to this invention, hung up at the railing. Fig. 2 shows the oil reservoir apart from the 35 life-belt. Fig. 3 is a transverse section on line A—B of Fig. 2.

The life-belt consists essentially of a float *a* rendered buoyant in any suitable known manner and provided at its circumference 40 with ropes *b* or other equivalent means to facilitate grasping. Inside the float *a*, in a chamber provided therein, an oil reservoir *c* is arranged. This oil reservoir is provided, both on top and at the bottom of the life-belt, with openings *d*, as indicated in Fig. 3. The openings *d* are normally closed 45 by a sliding lid *f*, which is guided in grooves suitably provided and which is fitted with a ring or hook *g*. To this ring or hook *g* is attached a cord or chain *h*, which is securely fastened on deck or at the railing at the place where the life-belt is hung up. An opening *e* in the oil reservoir *c* accessible 50 through the float *a* serves for filling in the oil. A screw-lid or other equivalent tight

fitting means is used for closing the opening *e* after the oil reservoir *c* has been filled to the required degree.

On throwing the life-belt into the water the cord or chain *h*, which is securely fastened on deck or at the railing as stated, 60 pulls the sliding lid *f* off and thus uncovers the openings *d* so that the oil issues from the reservoir *c* while the life-belt swims on the water. The oil distributed calms the 65 water around the life-belt in the usual known manner and in this way facilitates the saving action.

After use the life-belt taken from the water can be reinstalled subsequent to its oil 70 reservoir *c* having been refilled and the oil-issuing openings *d* having been tightly closed again by means of the sliding lid *f*.

The employment of the sliding lid *f* for closing the oil-issuing openings *d* in the reservoir *c* entails the advantage that the control of the oil charge and of the applicability 75 of the device can be easily and quickly effected.

While I have shown in the accompanying drawings the preferred form of my invention, it will be understood that I do not limit myself to the precise form shown, for many of the details may be changed in form or position without affecting the operativeness 80 or utility of my invention, and I therefore reserve the right to make all such modifications as are included within the scope of the following claims, or of mechanical equivalents to the structure set forth. 85

90 What I do claim as my invention, and desire to secure by Letters Patent, is:

1. In a life-belt or equivalent life-saving device the combination of a float, an oil reservoir fixed inside the said float in a chamber provided therein, said oil reservoir provided with normally closed oil-issuing openings at the top and bottom of the float, and means in fixed connection with the deck or railing at the plate where the life-belt is 95 hung up for uncovering the oil-issuing openings on throwing the life-belt into the water, substantially as described and shown.

2. In a life-belt or equivalent life-saving device the combination of a float, an oil reservoir fixed inside the said float in a chamber provided therein, said oil reservoir provided with normally closed oil-issuing openings at the top and bottom of the float, and a sliding lid movable in suitable guides for 100 105 110

closing the aforesaid oil-issuing openings of the oil reservoir, and means securely attached to the sliding lid in fixed connection with the deck or railing at the place where 5 the life-belt is hung up, substantially as described and shown.

In witness whereof I have hereunto signed

my name this 17th day of September 1912, in the presence of two subscribing witnesses.

FRIEDRICH CHRISTIANSEN.

Witnesses:

ERNEST H. L. MUMMENHOFF,
EDUARD HOPP.
